UNITED STATES PATENT OFFICE.

DANIEL W. WILKINS, OF BOSTON, MASSACHUSETTS.

SHIELD FOR SHIRT-STUDS.

SPECIFICATION forming part of Letters Patent No. 276,741, dated May 1, 1883.

Application filed March 12, 1883. (No model.)

To all whom it may concern:

Be it known that I, DANIEL W. WILKINS, of Boston, in the county of Suffolk and State of Massachusetts, have invented a new and 5 Improved Shield for Shirt-Studs, of which the following is a full, clear, and exact description.

The object of my invention is to provide a new and improved device for preventing the screws or spirals of shirt-studs from irritating 10 the skin and cutting holes in the underwear.

The invention consists in a shield, into which the screw or spiral of the stud can be screwed after having been passed through the aperture 15 in the shirt-bosom, which shield is preferably constructed of two disks secured to each other at the edges, one of which disks is provided with an aperture, through which the screw of the stud can be passed.

Reference is to be had to the accompanying 20 drawings, forming part of this specification, in which similar letters of reference indicate corresponding parts in all the figures.

Figure 1 is a front view of part of a shirt-bosom the stud-spirals in which are passed 25 into my improved shield for shirt-studs. Fig. 2 is a sectional view of the same on the line $x-x$, Fig. 1. Fig. 3 is a face view of the shield.

Two disks, A, of leather, cloth, or analogous material, are sewed together at the edges, or 30 secured together at the edges in any other suitable manner, one of which disks is provided with an aperture, a, in the middle. If desired, a disk of thin metal can be held between the

two disks to prevent the screw or spiral B of the shirt-stud C from being forced through 35 the disks. The shield formed of the disks A is held on the back of the shirt-bosom D in such a manner that the screw or spiral B passed through the aperture in the bosom can pass into the aperture a in the shield, and is 40 then screwed into the shield, as shown in Fig. 2. The shield prevents the end or point of the screw or spiral from irritating the skin or cutting holes in the underwear. The shield also assists in preventing accidental unscrewing of 45 the stud.

Having thus described my invention, what I claim as new, and desire to secure by Letters Patent, is—

1. A shield for shirt-studs, made substantially 50 as herein shown and described, and consisting of a disk to which the inner end of the spiral or screw of the stud can be screwed after the same has been passed through the aperture in the shirt-bosom, as set forth.

2. A shield for shirt-studs, made of two 55 disks of cloth, leather, or like material, attached to each other at the edges, one of which disks is provided with an aperture, substantially as herein shown and described, and for 60 the purpose set forth.

Boston, March 8, 1883.

DANIEL W. WILKINS.
